Patented Aug. 11, 1914.

UNITED STATES PATENT OFFICE.

WALTER E. VERCLAIRE, OF CHICAGO, ILLINOIS.

AEROPLANE.

1,106,428.

Specification of Letters Patent.

Patented Aug. 11, 1914.

Original application filed December 23, 1912, Serial No. 738,201. Divided and this application filed March 25, 1914. Serial No. 827,089.

To all whom it may concern:

Be it known that I, WALTER E. VERCLAIRE, a citizen of the United States, and a resident of the city of Chicago, county of Cook, and State of Illinois, have invented certain new and useful Improvements in Aeroplanes, of which the following is a specification.

My invention relates to new and useful improvements in aeroplanes and constitutes a divisional application of the application filed by me, December 23rd, 1912, Serial No. 738,201.

The invention consists in the combinations and arrangements of parts hereinafter described and claimed.

The invention will be best understood by reference to the accompanying drawing forming a part of this specification, and in which,

20 Figure 1 is a longitudinal section of an aeroplane embodying my invention, Fig. 2 is a section of the same taken on line 2—2 in Fig. 1, Fig. 3 is an enlarged fragmental section of the controlling lever, its mounting and connections, and Fig. 4 is an enlarged fragmental section taken on line 4—4 in Fig. 2.

The preferred form of construction as illustrated in the drawing comprises a beam 30 5 extending longitudinally of the aeroplane and a keel 6 joined at its forward end to the forward end of said beam, having a portion curved downwardly from said beam and its remaining portion parallel with said beam. 35 A plurality of parallel spaced posts 7 extend between said beam and keel. Extending laterally of the beam 5 are ribs 8 upwardly curved and joined at their inner ends to the beam 5. The outer ends of the ribs 40 8 are connected by means of tie wires 9 to the keel 6.

In the forward part of the aeroplane is a vertical post 10 and a shaft 11 journaled horizontally in said post. Mounted on the shaft 11 is a propeller mounting upon which is operatively mounted a propeller 12 and a motor 13. The motor and propeller are fully described in my application above referred to, and do not form a part of the invention claimed in this application.

On the shaft 11 is a lever 14 adapted to tilt the propeller 12 on shaft 11. The lever 14 is connected by means of cables 15 with a controller lever 16. Said controller lever 55 is mounted for pivotal movement in a slot

17 of a post 18. Post 18 is provided with trunnions 19 which are journaled in the beam 5 and keel 6, substantially as indicated.

At the rear end of the aeroplane is a vertical post 20 slotted and provided with a triangular rudder plane 21 secured therein and adapted to be operated by pivotal movement of post 20. At the lower end of post 20 are arms 22 and the latter are connected to corresponding arms 23 formed on the lower end of post 18 so that upon horizontal swinging of lever 16, corresponding pivotal movement will be caused by post 20 effecting operation of the rudder plane 21.

At the central portion of post 20 is provided a perforation in which is rotatably mounted a slotted shaft 24. In the slot of shaft 24 are mounted the two sections of a stabilizing plane 25. The sections of stabilizing plane 25 are triangular in shape, one section being disposed on each side of rudder plane 21, as indicated. The rear edges of both sections of stabilizing plane 25 are connected by means of cables 26 to the rearward end of controller lever 16 passing over pulleys 28, said cables passing downwardly from the rear edge of stabilizing plane 25 to the lower part of the aeroplane frame in a manner to cause a downward pull on the rear portion of said stabilizing plane. 85 The rear edges of the sections of stabilizing plane 25 are connected by means of cables 29 to the forward end of controller lever 16 passing over pulleys 30, the cables 29 passing upwardly from the rear edges of the sections of stabilizing plane 25 to the upper portion of the aeroplane frame and thence to the controller lever 16 in a manner to cause upward movement of the rear portion of stabilizing plane 25 upon operation of cables 29. 90

In operation, to effect steering of the aeroplane, the controller lever 16 is moved laterally, causing corresponding movement of the rudder plane 21 by means of the arms 100 22 and 23 and their connecting cables.

To effect tilting or inclining of the stabilizing plane 25, the controller lever 16 is moved vertically on its pivotal point in post 18. When it is desired to incline the stabilizing plane 25 so that its rearward edge is elevated, the controller lever 16 is moved downwardly such as to the dotted line positions of controller lever 16, stabilizing plane 25 and cables 26 and 29, in Fig. 1. When it 110

is desired to tilt the stabilizing plane in the opposite direction, lever 16 is moved upwardly, as will be readily understood.

While I have illustrated and described the preferred form of construction for carrying my invention into effect, this is capable of variation and modification without departing from the spirit of the invention. I, therefore, do not wish to be limited to the exact details of construction set forth, but desire to avail myself of such variations and modifications as come within the scope of the appended claims.

Having described my invention what I claim as new and desire to secure by Letters Patent is:

1. In an aeroplane, a frame; a longitudinally slotted post pivoted in said frame; a rudder plane secured in the slot of said post; a horizontally disposed slotted shaft journaled centrally of and in said post; a stabilizing plane secured in the slot of said shaft; and means for operating each of said planes separately from the other, substantially as described.

2. In an aeroplane, a frame; a longitudinally slotted post pivoted in said frame; a rudder plane secured in the slot of said post; a horizontally disposed slotted shaft journaled centrally of and in said post; a stabilizing plane secured in the slot of said shaft; lateral arms on said post; steering cables connected with said arms; and controlling cables connected with the rear edge of said stabilizing plane, substantially as described.

3. In an aeroplane, a frame; a longitudinally slotted post pivoted in said frame; a rudder plane secured in the slot of said post; a horizontally disposed slotted shaft journaled centrally of and in said post; a stabilizing plane secured in the slot of said shaft; lateral arms on said post; steering cables connected with said arms; pulleys at the top and bottom portions of said post; and controlling cables over said pulleys and connected with the rear edge of said stabilizing plane, substantially as described.

4. In an aeroplane, a slotted vertical post rotatably mounted therein; a rudder plane secured in the slot of said vertical post; controlling arms on said vertical post; a second slotted vertical post rotatively mounted in the aeroplane; arms on said second vertical post; cables connecting the arms of said first vertical post with the arms of said second vertical post; stabilizing planes pivotally mounted on said first vertical post; a lever fulcrumed in the slot of said second vertical post for vertical swinging and connected to rotate said second vertical post; and cables connecting said lever with said stabilizing planes, substantially as described.

In testimony whereof I have signed my name to this specification in the presence of two subscribing witnesses.

WALTER E. VERCLAIRE.
